UNITED STATES PATENT OFFICE

2,605,051

ROCK CRUSHER

Nelson H. Bogie, Lexington, Ky.

Application September 29, 1947, Serial No. 776,787

2 Claims. (Cl. 241—217)

1

This invention relates to comminuting apparatus and more particularly to machines for crushing hand and friable materials such as ore, rock, coal and the like.

Having in mind the defects of the prior art apparatus it is an object of this invention to provide a comminuting apparatus that actually crushes rock and with substantially no abrasive action thereon.

It is another object of the invention to provide a rock crushing machine that has a positive feed action.

It is still another object of the invention to provide a rock crushing machine that has jaws which are directly opposed so as to positively crush the rock.

It is a further object of the invention to provide a rock crushing machine wherein the stationary jaw is adjustably mounted.

It is a still further object of the invention to provide a rock crushing machine wherein both jaws are adjustably mounted relative to each other.

It is yet another object of the invention to provide a rock crushing machine wherein the lower crushing end of the movable jaw is positively moved laterally at a substantially higher rate of speed than the longitudinal or upward and downward movement of the jaw by an eccentric rotary motion of its upper end.

It is still another object of the invention to provide a rock crushing machine wherein the lower crushing end of the movable jaw is moved through a crushing stroke toward the stationary jaw only when the movable jaw is not being moved longitudinally.

It is a still further object of the invention to provide a rock crushing machine wherein the lower crushing end of the movable jaw is retracted from the stationary jaw while it is subject to longitudinal movement to preclude abrasion of the rock and to positively feed it.

It is a still further object of the invention to provide a rock crushing machine including angular hopper forming portions, and substantially parallel crusher forming portions.

It is a collateral object of the invention to provide a rock crusher jaw having readily replaceable wear plates to eliminate loss of time and production in replacing these plates.

It is an object of the invention to provide a rock crushing machine having economy of construction.

2

structure, simplicity of design and efficiency of operation.

The foregoing objects and others ancillary thereto are preferably accomplished, according to a preferred embodiment of the invention, by a rock crushing machine having an adjustably mounted stationary jaw, and a movable jaw which is driven and shifted or moved at both its upper and lower ends but in different, opposite or the same directions and in timed relation. The upper drive may comprise an eccentric which imparts longitudinal movement to the jaw with relatively stationary periods between the longitudinal movements while the eccentric is passing over and under its pivotal center and when the jaw is moved in and out. The lower drive imparts a horizontal reciprocal movement to the bottom of the jaw in the same direction, opposite to the directions of movement of the top of the jaw, or while the latter is moving up or down and is timed to move the jaw toward the stationary jaw during the relatively stationary periods and retract the jaw during the longitudinal movement periods. The lower drive preferably comprises an eccentric that rolls freely against the bottom outer surface of the movable jaw and is preferably driven at twice the speed of the upper eccentric so as to impact the rock twice during each revolution of the upper eccentric.

The stationary jaw, preferably, is pivotally mounted at its upper end and propped at its lower end by an adjustable or adjustably positioned toggle whereas the lower eccentric of the movable jaw is adjustably positioned to vary to the position of this lower end of the movable jaw. The movable jaw may be retained against the lower eccentric by gravity but it is preferred that it be positively retained in contact therewith as by a spring. The lower ends or end portions of the jaws are both positioned angularly, preferably at obtuse angles, relative to their body and upper portions, to provide substantially parallel crushing plates so that the rock is positively crushed and not abraded. In order to permit ready replacement of the wear plates, they are formed in units and adapted to be positioned by a single clamp.

The novel features that are considered characteristic of the invention are set forth with particularity in the appended claims. The invention itself, however, both as to its organization

and its method of operation, together with additional objects and advantages thereof, will best be understood from the following description of a specific embodiment when read in connection with the accompanying drawings, wherein like reference characters indicate like parts throughout and in which:

Fig. 1 is a cross-sectional view taken vertically through a rock-crushing machine in accordance with the present invention;

Fig. 2 is a fragmentary side view in elevation showing the adjustable mounting of the lower eccentric shaft; and

Figs. 3, 4, 5 and 6 are diagrammatic views illustrating the operation of the movable jaw.

Referring now to the drawings, and specifically with reference to Figure 1, a rock crushing machine, in accordance with a preferred embodiment of the present invention, comprises a frame 10 including end walls 11, a front wall 12 and a rear wall 13. The walls are heavily reinforced by ribs 14 to provide a rigid, strong construction that will withstand the vibration, crushing stresses and hard use to which such machines are subjected. The top of the frame 10 is open to receive rock to be crushed and the bottom of the frame is open to discharge crushed rock.

A pair of crushing jaws 15 and 16 are mounted within the frame 10 and extend between the end walls 11 thereof. One of these jaws 15 is a stationary jaw and the other of these jaws 16 is a movable jaw. These jaws angle apart toward their upper ends to form a hopper for receiving the rock to be crushed therebetween and include elongated flat upper portions, 17 and 18 respectively, which are angularly arranged to form the hopper. At their lower ends they each include short flat portions 19 and 20 respectively, which are angularly arranged at obtuse angles relative to said elongated or long flat upper portions 17 and 18, respectively, of the jaws 15 and 16 so as to be substantially parallel with each other to provide directly opposed crushing surfaces which are arranged in a substantially vertical position.

The stationary jaw 15 comprises a frame 21 having a front inner recess 22 extending along the angled portions for receiving the corresponding angled but otherwise usual wear plates 23. Whereas the usual stationary jaw is formed integrally with the machine frame, one of the advantages of the present invention resides in the fact that the stationary jaw 15 is adjustably mounted within the frame 10. The jaw frame 21 has a bore 24 extending longitudinally widthwise or transversely through its upper end to receive and be supported by a shaft 25 which has its ends supported by the end walls 11 of the machine frame 10. Consequently, the jaw 15 may be pivotally adjusted about the shaft 25 to vary its angular position relative to the movable jaw 16.

To regulate the position of the jaw 15, it is provided with a groove 26 in its lower rear surface to form a seat for one end of a toggle 27 which has its other end seated in a groove 28 formed in a block 29 that is adjustably positioned relative to the inside of the front wall 12 by a plurality of shims 30, the block 29 and shims 30 being mounted on a ledge 30' extending inwardly of the front wall 12 of the machine frame 10. The jaw is held rigidly against the toggle 27 by a tie bolt or rod 27' pivoted to the outside of frame 21 of jaw 15 and adjustably connected or tied to or through the front wall 12 of the frame 10.

The toggle 27 is adapted to break or collapse under a predetermined pressure so that it will support the jaw 15 during normal operation but will release the jaw in the event of a jam or other abnormal operation to prevent damage to the machine.

The movable jaw 16 is similar to the stationary jaw 15 in that it comprises a frame 31 that has a similarly angled front recess or seat 32 for correspondingly angled wear plates 33. In order to facilitate rapid replacement of the wear plates 33 they are formed as two separate plates having opposed angular surfaces 34 for engagement by a wedge clamp 35 which may be carried by a bolt 36 that may extend through the face of the frame 31 and be secured by a nut 37. The face of the wedge 35 preferably coincides with the wear faces of the wear plates 33 and also form a wear surface. The lower of the wear plates 33 preferably includes an angular portion to form the crushing surface 20. Although this mounting of the wear plates is shown only with respect to the movable jaw 16, obviously this construction may be incorporated in the stationary jaw 15.

The movable jaw 16 is mounted at its top on an eccentric in the usual manner, the frame 31 having a sleeve 38 at its upper end to receive the outer race 39 of an antifriction bearing 40, the inner race 41 of which surrounds an eccentric 42 formed integrally with a shaft 43. Obviously the eccentric need not be formed integrally with the shaft 43 but may be keyed or otherwise mounted thereon, and, if desired, a crank may be substituted for the eccentric. The shaft 43 is journalled in the end walls 11 of the machine frame 10 and may carry a fly wheel 44 and be driven in any suitable manner.

The lower end of the jaw frame 31 is angularly positioned to accommodate the crushing face 20 and to provide a bearing surface 45 which is preferably formed by a hardened metal plate 46 seated in a recess 47 of the frame 31. The surface 45 of the plate 46 bears against the outer race 48 of an anti-friction bearing 49, the inner race 50 of which is mounted on an eccentric 51 carried by a shaft 52 that is journalled in the end walls 11 of the machine frame 10. As a matter of convenience and economy, the upper and lower shafts 43 and 52, eccentrics 42 and 51, and bearings 40 and 49 are identical in size.

The shaft 52 is driven in order to impart a lateral movement to the crushing face 20, and preferably this shaft is driven from and in timed relation with the upper driven shaft 43. This may be accomplished by any suitable means, and for purposes of illustration, is shown as comprising a gear train drive although a chain or other drive may be used. A gear 53 is fixed on the shaft 43 to be driven thereby and this gear 53 meshes with a gear 54 that is mounted on a shaft 55 supported by one of the end walls 11 of the machine frame 10. The gear 54 meshes with a gear 56, that is fixed on the lower shaft 52. The gear train preferably comprises a reduction so that the lower shaft 52 is driven at a higher rate of speed than the shaft 43, preferably at the rate of 2 to 1. It will be noted that as the shaft 52 is driven it will revolve the eccentric 51 and bearing 49 so that the outer race 48 will roll up and down on the bearing surface 45 of the wear plate 46 while reciprocating the crushing surface 20.

Although the lower end of the jaw 16 will tend to follow the reciprocal movement of the outer race 48 due to gravity, it is preferred to positively maintain contact between the surface 45 of the

bearing plate 46 and the periphery of the race 48. This may be accomplished by a lengthwise adjustable pull rod 57 that is connected to the jaw frame 31 by a pivot 58 mounted in a bracket 59 carried by the frame 31. The rod 57 extends laterally through an aperture 60 and socket 61 in the rear wall 13 of the machine frame 10 and preferably extends beyond said rear wall 13 for a short distance. A helical spring 62 biases the pull rod 57 outwardly to pull the jaw 16 against the race 48, the spring 62 surrounding the rod 57, seating in the socket 61 and bearing against a collar 63 and nut 64 threaded on the rod 57 to vary or adjust the tension and position of portions 18 and 20 of movable jaw 16 relative to portions 17 and 19 of stationary jaw.

In order to effect adjustment of the lower end of the movable jaw 16 and the portion 20 of wear plate 33 of movable jaw 16 relative to the portion 19 of wear plate 23 of stationary jaw 15 it is obviously necessary to adjustably mount the shaft 52 in the end walls 11 of the machine frame 10. Consequently, the ends of the shaft 52 are preferably seated in bearings 65, preferably anti-friction bearings, which may be seated in corresponding arcuate slots 66 in said end walls 11 concentric to shaft 55. Depending upon the type of drive system employed, the slots 66 are preferably arcuate and are provided with means for adjustably positioning the bearings 65 therein. In the present instance, as best shown in Fig. 2, the slots 66 are curved on a radius from the axis 55a of the gear shaft 55 so that the gear 56, on the shaft 52 may follow or roll on the gear 54 on the shaft 55, when the bearings 65 are adjusted in the slots 66. The ends 67 of the slots 66 are preferably parallel in order to flatly engage shims 58, a plurality of the said shims 68 being inserted in the slots 66 as desired on either or both sides of the bearings 65.

In assembling the machine of the present invention the shafts 43 and 52 are preferably arranged so that their respective eccentrics 42 and 51 have a predetermined relationship when said shafts are driven. This is desirable in order to obtain maximum operating efficiency, a positive feed to the crushing surfaces 19 and 20, and to eliminate unnecessary abrasion of the wear plates 23 and 33. It is preferred that the relationship be such that the lower eccentric 51 will act to move the crushing surface 20 toward its opposed surface 19 only when the upper eccentric 42 is passing through a cross-stroke over and under its shaft 43. By this arrangement the crushing stroke is delivered only when the jaw 16 is not subject to longitudinal movement, and when the jaw is moved longitudinally the crushing part 20 is retracted to relieve the pressure on the rock between the jaws and thereby eliminate rubbing abrasion of the rock.

The above described operation has the additional advantage of positively feeding the rock to the crushing portions 19 and 20 so that the rock will never jam or need additional means for maintaining an even flow through the machine. This action is effected by the retraction of the lower portion 20 during the longitudinal movement of the jaw 16 so that the throat 19-20 of the jaws is enlarged whenever there is a longitudinal agitation of the rock therebetween. Therefore, when the rock is loosened by longitudinal agitation, it is free to gravitate between the expanded crushing portions.

Furthermore, the movement of the jaw 16 is preferably effected in such a manner as to obtain

maximum feeding action by driving the upper eccentric 42 in a direction so that it moves downward when passing through its forward position so that the rock receives a positive downward movement when the upper portion of the jaw 16 passes through its forward position so as to positively push the rock down between the expanded portions 19 and 20. Consequently, the jaw 16 is moved upwardly while passing through its rearward position so that it is at its maximum spacing from the stationary jaw 15 and thereby permits the ready settling of the rock, the upward movement imparted to the rock adjacent the jaw 16 merely serving to agitate the impacted rock to promote its settling.

The hereinbefore described action of the jaws is diagrammatically illustrated in Figs. 3 through 6, the jaw 15 being in a constant position throughout these diagrams. Fig. 3 illustrates the jaws and eccentrics in the same position as that shown in Fig. 1 and this position will be employed as a starting point in describing the cycle of operation, the shafts 43 and 52 being driven in the direction of the small arrows associated therewith, according to the preferred operation of the invention. In the position of the apparatus shown in the drawings, the shafts are preferably driven counter-clockwise.

Referring specifically to Fig. 3 it will be seen that the upper eccentric 42 is in the extreme of its forward position and, preferably, is in its downward stroke. Consequently, the jaw 16 is moving downwardly, as indicated by the downward vertical arrow V, and the upper end of the jaw is in its extreme forward position. Simultaneously, the lower eccentric 51 is in the extreme of its rearward movement, so that the crushing portion 20 is retracted to its extreme rearward, open position as indicated by the horizontal, rearward arrow R. Therefore, as the jaw 16 is moving downwardly with its upper end in forward position it will tend to push the rock down between the open crushing portions 19 and 20.

It will be understood that during the longitudinal movement of the jaw 16, its lower rear bearing surface 45 will travel over the periphery 48 of the lower bearing 49, the periphery or outer race 48 merely rolling along the reciprocating surface 45. Obviously, the direction of rotation of the lower shaft 52 is immaterial as far as being critical, except as stated, as the bearing 49 is not fixed to either the shaft or the jaw. However, with the gear drive illustrated in Fig. 1, the shaft 52 will rotate, and the eccentric 51 will revolve, in the direction of the arrow associated therewith in Fig. 3 and rotation in this direction reduces friction between the roller or race 48 and the wear surface 45.

As the shaft 43 rotates a quarter revolution to revolve its eccentric 42 to its lower position, as shown in Fig. 4, the shaft 52 rotates half a revolution forwardly and downwardly to revolve its eccentric 51 to its forward position due to the 2 to 1 reduction drive therebetween. When the upper eccentric passes through its downward position the longitudinal downward movement of the jaw 16 is, for all practical purposes, substantially completed and ceased and instead a lateral horizontal outward or retracting movement is imparted to the upper end of the jaw 16 as indicated by the rearward, horizontal arrow H. During this period of substantially no longitudinal movement of jaw 16 the lower eccentric 51 is operated to turn forwardly and down-

wardly and impart a forward lateral, horizontal movement to the lower end of the jaw 16 to deliver the forward, crushing stroke to the crushing surface or portion 20 toward stationary crushing surface or portion 19 of jaw 15 and the rock 5 or other material therebetween, as indicated by the horizontal, forward arrow F. Thus, the crushing stroke is delivered while the jaw is substantially devoid of longitudinal movement so that there is substantially no rubbing abrasion 10 of the rock or wear plates 33.

With continued rotation of the upper shaft 43 its eccentric 42 passes beyond its cross stroke to its extreme rearward position, as shown in Fig. 5, while moving upwardly. Consequently the jaw 16 receives an upward and outward or rearward longitudinal movement as indicated by the upward, vertical arrow V'. Therefore, the lower shaft 52 simultaneously rotates half a revolution to revolve its eccentric 51 outwardly or rearwardly and upwardly to its rearward position to permit the spring 62 and pull rod 57 to retract the crushing portion 20 with surface 45 and portion 20 following eccentric 51 and outer race 48 of bearing 49 as indicated by the horizontal, rearward arrow R' tending to release and discharge the crushed material. Thus, while the jaw 16 is moved longitudinally upwardly the crushing portions are again open so as to avoid abrasive pressure on the rock and wear plates and permit settling of the rock between the crushing portions 19 and 20. Furthermore, as the upper end of the jaw 16 is retracted while moving upwardly, the rock mass is permitted to expand and settle 35 rather than to be fed backwardly as in the prior apparatus. As a matter of fact, the upward movement of the jaw is imparted only to the rock in immediate contact therewith and this movement has the advantage of agitating the rock mass and thereby promotes settling of the mass.

Continued rotation of the upper shaft 43 revolves its eccentric 42 upwardly and inwardly or forwardly to its upper position, as shown in Fig. 6, whereupon it is in the midst of its forward cross-stroke, as indicated by the forward horizontal arrow H', and longitudinal movement of the jaw 16 is ceased. Simultaneously, the lower shaft 52 rotates a half revolution to revolve its eccentric 51 forwardly or upwardly, inwardly and downwardly to impart a crushing stroke to the portion 20 as indicated by the horizontal forward arrow F. Thus, the crushing stroke is again delivered while the jaw 16 is free of longitudinal movement. Continued rotation of the shafts 43 and 52 and eccentrics 42 and 51 moves the jaw 16 into its downward, open-throated feeding position with portion 20 moving outwardly or rearwardly away from portion 19 which is shown in Fig. 3 and completes the cycle of operation.

In view of the foregoing description, it will be seen that the crushing portion 20 delivers a crushing stroke twice during each cycle of operation of the jaw 16 while the latter is moving both outwardly and inwardly at its upper portion with eccentric 42, that is, for each revolution of the shaft 43 as seen in Figures 4 and 6. The speed of operation may be varied through a relatively wide range, however, it is preferred that this speed should be regulated within specific limits or at least above a certain minimum. More specifically, it has been found that superior results are obtained if the rock receives two impacts while gravitating between the crushing portions 19 and 20.

To graphically illustrate, a piece of rock X is shown at the entrance of the crushing throat 19-20 in Fig. 3. Between gravity and the feeding and settling action of the jaw 16, this rock X is delivered into the upper end of the throat 19-20 and impacted therein, as shown in Fig. 4, to break or crush it into pieces x. When the throat 19-20 is again opened, the pieces x gravitate and are fed downwardly as shown in Fig. 5 and are again impacted in the lower end of the throat 19-20, as shown in Fig. 6, to further crush it, if necessary, to the desired size.

In a preferred size and form of machine it has been found that if the shaft 43 is driven at 200 R. P. M. and the shaft 52 at 400 R. P. M., the rock falls about 4 inches between impacts or during a complete cycle of operation. Therefore, it has been found that the crushing portions 19 and 20 obtained the desired results when they are about 6 inches in height. Obviously, the rock may be impacted more than twice but this action is not necessary as the desired results are obtained, for all practical purposes, by a double impact and the excessive wear on the machine due to a higher rate of operation more than offsets any advantage. In addition, it is evident that the invention may be practiced with two movable jaws, both operating in the manner of the herein-described jaw 16, however, the use of the stationary jaw 15 is preferred so as to simplify and economize on construction and operation while obtaining equally satisfactory results.

It will be understood that the present invention is equally adaptable for crushing ore, coal or other friable materials although described herein as a rock crusher.

Although a certain specific embodiment of the invention has been shown and described, it is obvious that many modifications thereof are possible. The invention, therefore, is not to be restricted except insofar as is necessitated by the prior art and by the spirit of the appended claims.

That which is claimed as new, is:

1. Rock crushing apparatus comprising a pair of jaws defining a hopper for receiving rock therebetween and each including an upper end portion and a lower end portion disposed at an angle to the upper end portion, said jaws being disposed with their lower end portions in relatively close substantially parallel juxtaposition and forming crusher portions, at least one of said jaws being movable, upper rotatable eccentric means within the upper end of said movable jaw, lower rotatable eccentric means slidably engaging the lower portion of said movable jaw adjacent said crusher portion, and means for driving said eccentric means and including means correlating the rate of said lower eccentric means at a two-to-one ratio relative to the rate of said upper eccentric means, the eccentric portions of said eccentric means being in uniform angular relation about their axes.

2. Rock crushing apparatus as defined in claim 1 wherein said drive means rotates said eccentric means in the same direction and in which the eccentric portions revolve over the axes of said means toward said jaws.

NELSON H. BOGIE.
